(57) **CLAIM**

The ornamental design for an electrical connector, as shown.

DESCRIPTION

FIG. 1 is a top right front perspective view of a first embodiment of an electrical connector showing my new design; FIG. 2 is a bottom plan view thereof;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a top plan view thereof;

FIG. 8 is a top right front perspective view of a second embodiment of an electrical connector showing my new design;

FIG. 9 is a bottom plan view thereof;

FIG. 10 is a right side elevational view thereof;

FIG. 11 a front elevational view thereof;

FIG. 12 is a left side elevational view thereof;

FIG. 13 is a rear elevational view thereof; and,

FIG. 14 is a top plan view thereof.
